W. FALKENBERG

ELECTRODE

Filed June 6, 1923

INVENTOR.
Wilhelm Falkenberg
BY
George C. Heinrich
ATTORNEY.

UNITED STATES PATENT OFFICE.

WILHELM FALKENBERG, OF NEW YORK, N. Y., ASSIGNOR TO ALBERT WIELICH, OF NEW YORK, N. Y.

ELECTRODE.

Application filed June 6, 1923. Serial No. 643,748.

This invention relates to improvements in vacuum electrodes which are filled with a precious gas and used for the therapeutical treatment of diseases. They are intended 5 to replace the electrodes used heretofore which produce a bluish white or reddish blue colored rays.

It is the principal purpose of this invention to produce an electrode of this character which can be used with high frequency current apparatus to produce yellowish light rays.

Another object of the invention is the provision of such an electrode which is filled 15 with helium gas and the rays of which are yellowish in the spectrum and have a healing capacity for certain kinds of diseases.

These and other objects and advantages 20 of my invention will become more fully known as the description thereof proceeds and will then be specifically pointed out in the appended claims.

In the accompanying drawing, forming a material part of this disclosure:

25 The single figure illustrates in sectional side elevation the preferred form of an electrode constructed according to the present invention.

The vacuum 10 of any suitable shape or 30 form, carries a cathode 11 held within the tube by means of a holder 12 and connected by means of a wire 13 or the like with a metal sleeve 14 upon the restricted front end of the electrode, adapted to be connected

35 with a high frequency current apparatus.

The electrode as illustrated in its preferred form is principally intended for the

treatment of skin diseases, it may however, as stated above, have any suitable form allowing a treatment of the various cavities 40 and other parts of the human body.

It is therefore understood that I do not wish to limit myself to the specific form illustrated as an example, but that such changes may be made which fall within the 45 scope of my invention as defined in the appended claims.

Having thus described my invention, what I claim as new and desire to secure by Letters Patent is:

1. As an article of manufacture, an electrode comprising a tube containing a gas and having a restricted laterally extending handle portion, a holder within the tube, a cathode within said holder, a metal sleeve 50 upon the terminal of the laterally extending portion, a wire connecting said sleeve and cathode, and a quartz plate covering an opening formed in one end of the tube, the tube proper and lateral extension being 55 charged with helium gas.

2. An electrode comprising a tubular body rounded at one end and flaring at the opposite end, an electrode holder extending longitudinally and centrally over the body 65 from the rounded end and a handle member formed as a lateral extension open to and communicating with the body and projecting from one side of the body intermediate the ends and at a point substantially mid-length of the electrode holder.

In testimony whereof I have affixed my signature.

WILHELM FALKENBERG.
